CLOCK

Christian Jauch, Winsted, Conn., assignor to William L. Gilbert Clock Corporation, Winsted, Conn., a corporation of Connecticut

Application February 28, 1941, Serial No. 381,069

4 Claims. (Cl. 58—125)

The present invention relates to clocks and more particularly to a twenty-four hour clock of the type used in airplanes and wherein the clock mechanism is utilized for operating a sun compass or the like.

The object of the present invention is to provide in conjunction with the clock mechanism suitable shiftable connecting means whereby the constant rotation of the clock mechanism or, more specifically, the minute shaft may be utilized to operate an auxiliary shaft in either of two directions.

A still further object is to provide a clock of this nature wherein the shiftable connecting means is so extremely compact that it may be incorporated within the clock casing without unduly increasing the size or weight of the clock.

A still further object is to incorporate the shiftable connecting means in such a manner that when the clock has been installed within the airplane the means for controlling the shiftable means mechanism is accessible from the front of the clock.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawing:

Figure 1 is a front view of a clock incorporating the invention herein;

Fig. 2 is a side view with the casing partially in section to show the shiftable connecting means;

Fig. 3 is a view looking from the rear of the clock with the back plate removed and showing the connecting means so positioned that the auxiliary shaft will operate in the same direction as the minute shaft;

Fig. 4 is a view similar to Fig. 3 with the connecting means shifted to a position to operate the auxiliary shaft in a direction reverse to the minute shaft;

Fig. 5 is a view taken on line 5—5 of Fig. 3; and

Fig. 6 is a view taken on the line 6—6 of Fig. 4.

Referring to the drawing, the clock comprises generally a casing A in which there is mounted a clock mechanism B and means C for connecting the clock mechanism to an auxiliary shaft D. More particularly, the clock casing comprises a cup-shaped shell 10 provided at its rear peripheral edge with a radially extending flange 12 and having secured to its front face a dial 14. The clock mechanism B within the casing includes the spaced front and rear supporting plates 15 and 18 secured together by pillars 20.

As the clock works which are supported be-

tween the plates 15 and 18 may be of any usual type, wherein the minute hand is rotated once every hour and the hour hand once in every twenty-four hours, the parts which are not essential to an understanding of the invention have not been shown, but are generally designated by the rectangle 22.

Herein the minute shaft 24, which makes a single revolution per hour, is of such length that it extends through the front of the casing for receiving the minute hand and through the rear supporting plate 18 for carrying a gear 26 and an auxiliary shaft 28. The auxiliary shaft 23 is intended to be connected to another instrument, such, for example, as a sun compass, and for this reason it must be capable of being rotated in a reverse direction. To accomplish this, as well as for convenience in manufacture and assembly, the shaft 28 is provided with a central hollow bore 30 for telescoping it onto the extending end of the minute shaft 24 whereby it is concentric with and freely rotatable on said shaft. To rotate shaft 28, it further has an integrally formed gear 34 which is operatively connected through the connecting means C to the gear 26 which is directly secured to the minute shaft.

Referring now to the connecting means C, it comprises an elongated plate 36 provided at its opposite ends with elongated slots 38 and 40 for slidably mounting the plate on studs 42 threadably secured to the supporting plate 18. The plate 36 is normally urged to the position shown in Fig. 3 by a spring finger 44 secured at one end to the supporting plate 18 and having its free end 46 engaging the plate 36 adjacent the elongated slot 38. When the plate is so positioned, the gear 26 on the minutes shaft is connected to the gear 34 of the auxiliary shaft through a train of gear, generally designated as 48. This train of gears includes a gear 50 meshing directly with the gear 26 and a second gear 52 concentric with and secured to the gear 50 and meshing directly with the gear 34. When so connected, it will be seen that upon rotation of the minute shaft the auxiliary shaft 28 will be simultaneously rotated in a like direction; the gear ratio, however, being such that there is a twenty-four-to-one stepdown whereby the auxiliary shaft is rotated but once in twenty-four hours.

In order to rotate the auxiliary shaft in the opposite direction, the plate 36 is shifted to the position shown in Fig. 4 whereupon the gear train 48 is disconnected and a second gear train, generally designated as 54, is brought into operation. This gear train includes a gear 56 mounted on the plate 36 and meshing directly with the gear 26, a second gear 58 mounted on the plate 36 and meshing directly with the gear 56, and a third gear 60 concentric with and secured to the gear 58 and meshing directly with the auxiliary shaft

gear 34. When so connected, it will be seen that upon rotation of the minute shaft the auxiliary shaft will be rotated in the opposite direction, which, as with the gear train 48, also has a twenty-four-to-one stepdown whereby the auxiliary shaft will be rotated but once in twenty-four hours.

In order to shift the plate 36 from the position shown in Fig. 3 to that in Fig. 4, there is associated therewith a cam 62 eccentrically mounted on a shaft 64. The maximum radius of the cam 62 is such that when the cam is rotated counterclockwise, as viewed in Fig. 3, through 180° it will engage a shoulder 66 on the plate 36 to shift the latter the length of the slots 38 and 40 to the position indicated in Fig. 4. In order to limit the rotation of cam 62, the plate 36 is provided with a contour 68 adjacent the shoulder 66 corresponding to that of the cam 62. Obviously when the cam is positioned within the contour 68 further rotation is limited as the plate 36 is restrained against sideways movement by the supporting studs 42. Obviously when the cam 62 is rotated reversely from the position shown in Fig. 4, the spring finger 44, being under tension, will shift the plate 36, and in this instance the rotation of the cam 62 is limited by its abutting against the side edge of the plate 36.

To conveniently manipulate the cam 62, the shaft 64 extends through the supporting plates 16 and 18 and terminates in a square key-receiving end 70 located in alignment with an opening 72 provided in the dial 14 (see Fig. 1). To maintain the cam 62 in operative position on the plate 18, the latter is held in position by a spring 74 positioned between a collar 76 (see Fig. 6) secured to the lever and spaced slightly from the supporting plate 18; the spring being so shaped that it normally urges the collar away from the plate and thus maintains the cam in flush contact with the rear face of the plate.

From the foregoing it will be seen that the connecting means C for alternately connecting the auxiliary shaft to the minute shaft is extremely compact and fully supported on the rear supporting plate 18 of the clock mechanism, thus permitting the entire device to be readily assembled within the casing 10. When so positioned, the auxiliary shaft 28 may be readily mounted on the extending end of the minute shaft and thereafter the casing closed by a rear plate 78. The rear plate is provided with a central opening 80 through which the auxiliary shaft extends; the latter shaft being held against outward movement by providing thereon an enlarged collar 82 positioned between the plate 78 and the gear 34. To secure the rear plate 78 in position, the pillars 20 may extend rearwardly of the supporting plate 18 and the plate 78 provided with openings adapted to be aligned therewith for receiving suitable securing screws 84.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

5. In a clock of the character described, a casing, a clock mechanism within the casing including a rear supporting plate, a minute shaft extending rearwardly of said rear supporting plate, a gear carried by said shaft, an auxiliary shaft concentric with and rotatably mounted on the extending end of said minute shaft, a gear carried by said auxiliary shaft, a first gear train 10 for interconnecting said minute shaft gear and said auxiliary shaft gear whereby said auxiliary shaft will be operated in the same direction as the minute shaft, a second gear train for connecting said minute shaft gear to said auxiliary shaft gear whereby said auxiliary shaft will be operated in a direction reverse to the minute shaft, and means for alternately bringing said gear trains into operative relation with said minute shaft gear and said auxiliary shaft gear.
20. In a clock of the character described, a casing, a clock mechanism within the casing including a rear supporting plate, a minute shaft extending rearwardly of said rear supporting plate, a gear carried by said shaft, a rotatably mounted auxiliary shaft, a gear carried by said auxiliary shaft, a first and second gear train for interconnecting said minute shaft gear and said auxiliary shaft gear, a common support for said gear trains including a member slidably mounted on said rear supporting plate, and means for shifting said support to selectively bring one of said gear trains into position to connect said auxiliary shaft gear with said minute shaft gear.
30. In a clock of the character described, a casing, a clock mechanism within the casing including a rear supporting plate, a minute shaft extending rearwardly of said rear supporting plate, a gear carried by said shaft, an auxiliary shaft positioned rearwardly of said rear supporting plate, a gear carried by said shaft, shifting means comprising a member slidably mounted on said rear supporting plate, means comprising a pair of gear trains carried by said shiftable means and operative when in one position of the shiftable means to interconnect said minute shaft and said auxiliary shaft for operation in the same direction and operative when in the other position of said shiftable means to connect said minute shaft and auxiliary shaft for operation in reverse direction, means for normally holding said shiftable member in one of its positions, and means for shifting said shiftable member to its other position.
40. In a clock of the character described, a casing, a clock mechanism supported within the casing and including a minute shaft, an auxiliary shaft supported within said casing and extending outwardly therefrom, a gear carried by each of said shafts, a first gear train for interconnecting said minute shaft gear and said auxiliary shaft gear whereby said auxiliary shaft will be operated in the same direction as the minute shaft, a second gear train for connecting said minute shaft gear to said auxiliary shaft gear, whereby said auxiliary shaft will be operated in a direction reverse to the minute shaft, a common support for said gear trains, means slidably mounting said support, spring means normally holding said support in position whereby one of said gear trains connects said minute shaft gear and auxiliary shaft gear, and means for shifting said support to disconnect said first gear train and connect said second gear train.
50. In a clock of the character described, a casing, a clock mechanism supported within the casing and including a minute shaft, an auxiliary shaft supported within said casing and extending outwardly therefrom, a gear carried by each of said shafts, a first gear train for interconnecting said minute shaft gear and said auxiliary shaft gear whereby said auxiliary shaft will be operated in the same direction as the minute shaft, a second gear train for connecting said minute shaft gear to said auxiliary shaft gear, whereby said auxiliary shaft will be operated in a direction reverse to the minute shaft, a common support for said gear trains, means slidably mounting said support, spring means normally holding said support in position whereby one of said gear trains connects said minute shaft gear and auxiliary shaft gear, and means for shifting said support to disconnect said first gear train and connect said second gear train.
60. In a clock of the character described, a casing, a clock mechanism supported within the casing and including a minute shaft, an auxiliary shaft supported within said casing and extending outwardly therefrom, a gear carried by each of said shafts, a first gear train for interconnecting said minute shaft gear and said auxiliary shaft gear whereby said auxiliary shaft will be operated in the same direction as the minute shaft, a second gear train for connecting said minute shaft gear to said auxiliary shaft gear, whereby said auxiliary shaft will be operated in a direction reverse to the minute shaft, a common support for said gear trains, means slidably mounting said support, spring means normally holding said support in position whereby one of said gear trains connects said minute shaft gear and auxiliary shaft gear, and means for shifting said support to disconnect said first gear train and connect said second gear train.
70. In a clock of the character described, a casing, a clock mechanism supported within the casing and including a minute shaft, an auxiliary shaft supported within said casing and extending outwardly therefrom, a gear carried by each of said shafts, a first gear train for interconnecting said minute shaft gear and said auxiliary shaft gear whereby said auxiliary shaft will be operated in the same direction as the minute shaft, a second gear train for connecting said minute shaft gear to said auxiliary shaft gear, whereby said auxiliary shaft will be operated in a direction reverse to the minute shaft, a common support for said gear trains, means slidably mounting said support, spring means normally holding said support in position whereby one of said gear trains connects said minute shaft gear and auxiliary shaft gear, and means for shifting said support to disconnect said first gear train and connect said second gear train.
